and Roger M. Floyd, Monroe, La., assignors to Olin-
kraft, Inc.

Filed Aug. 30, 1972, Ser. No. 285,008

Term of patent 14 years

Int. Cl. D9—03

U.S. Cl. D9—245

The box blank is formed of conventional thickness material and all of the dash lines represent fold lines including the dash lines adjacent to the slots.

The figure is a top plan view of a box blank embodying our new design, the bottom being substantially the same in appearance.

We claim:

The ornamental design for a box blank, substantially as shown and described.
